(57) **CLAIM**

The ornamental design for a spray pattern selection ring for water sprayer as shown and described.

DESCRIPTION

FIG. 1 is a perspective view of a spray pattern selection ring for water sprayer showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof;

FIG. 8 is a rear perspective view thereof; and,

FIG. 9 is a front perspective view thereof.

The broken line showing of the sprayer in FIGS. 8 and 9 illustrates the environment of the claimed design and forms no part of the claimed design. The remaining broken lines in FIGS. 1-9 illustrate portions of the spray pattern selection ring for water sprayer that form no part of the claimed design.
